UNITED STATES PATENT OFFICE.

JOSEPH O. ST. PIERRE, OF BOSTON, MASSACHUSETTS.

LIFTING-JACK.

1,181,265.

Specification of Letters Patent.

Patented Mar. 9, 1915.

Application filed March 4, 1912. Serial No. 631,861.

To all whom it may concern:

Be it known that I, JOSEPH O. ST. PIERRE, a subject of the King of Great Britain, and a resident of Boston, in the county of Suffolk and State of Massachusetts, United States of America, have invented certain new and useful Improvements in Lifting-Jacks, of which the following is a specification.

10 My invention relates to lifting jacks and particularly to that class of jacks which are known as ratchet screw jacks, and has for its object to produce a self lowering jack which will run down quickly under its load.

15 The invention consists in providing the jack with an extended train of reduction gearing, the low speed end of which is adapted to be driven by the main operating gear spindle of the jack only as the latter moves in a reverse direction to its movement in lifting the jack, and the high speed end of the train of gearing being adapted to drive a friction member with which a hand controlled brake cooperates. The train of 20 reduction gearing is sufficiently extended so that its inertia will substantially retard the speed of descent of the jack under its load and will make it possible for a light and freely operable friction brake to bring 25 the jack instantly to rest when descending under maximum loads. I utilize a ratchet means for automatically disconnecting the train of reduction gearing from the gear spindle when the latter is turned to raise the 30 jack under its load.

35 The invention further consists in certain novel features of construction and arrangement of parts which will be thoroughly understood by reference to the description of 40 the drawings and to the claims hereinafter given.

45 Of the drawings: Figure 1 represents a horizontal section of a lifting jack embodying the features of this invention, the cutting plane being on line 1—1 on Fig. 2. Fig. 2 represents a vertical section of the same, the cutting plane being on line 2—2 on Fig. 1. Fig. 3 represents an enlarged vertical section of the operating mechanism for controlling the lifting and lowering of the movable member of the jack, the cutting plane being on line 3—3 on Fig. 2. Fig. 4 represents a similar section looking in the opposite direction, the cutting plane being on line 4—4 on Fig. 2, and Fig. 5 represents an elevation partly in section of one embodiment 50 of the device for controlling or arresting the movement of said operating mechanism.

55 Similar characters designate like parts throughout the several figures of the drawings.

60 In the drawings, 10 represents a suitable base supporting a stationary standard 11 over the outer periphery of which is fitted a movable sleeve 12, to the upper end of which is threaded a cap 13. In the upper end of the standard 11 is mounted a nut 14 to which is threaded a lifting screw 15 having splined to its upper reduced end a gear 16 with which meshes a gear 17 formed upon 65 or secured to a revoluble shaft or spindle 18, the outer end of which is provided with a suitable operating mechanism 19 of any well known construction. Interposed between the upper face of the gear 16 and the inner 70 face of the cap 13 are two annular plates 20 and 21, between which are interposed a plurality of antifriction members 22.

75 Secured to the gear 17 by means of the screws 19 is a ratchet 20* with the teeth of 80 which engage a plurality of spring pressed pawls 21* pivotally secured to a spur gear 22* freely revoluble and mounted upon a reduced portion 23 of the cylindrical hub 24 forming a bearing for said spindle or shaft 85 18. This hub 24 is formed integral with a removable plate 25 secured to the flanged projection 26 forming a part of the movable member 12. The gear 22 meshes with a pinion 26* secured to or formed integral with a 90 revoluble member 27 to which is also secured a gear 28 meshing with a pinion 29 formed upon or secured to a revoluble member 30 to which is also secured a gear 31 meshing with the pinion 32 formed 95 upon or secured to a revoluble member 33 to which is also secured a gear 34, which in turn meshes with a pinion 35 formed upon or secured to a revoluble member 36. Secured to and revoluble with the member 36 100 is a disk 37 extending through a slot 38 in the wall of the boxlike flange 26. The flange 26 has formed thereon an ear 39 and the removable plate 25 has a similar ear 39* formed thereon. Each of the ears 39 and 39* 105 has mounted therein a cylindrical member 41 having a friction pad 42 secured to one end and a head 43 formed upon the other end between which and the ears 39 or 39* is a spring 44 adapted to normally retain said 110 pad 42 free from contact with the side face of the disk 37 interposed between said pads.

Each of the ears 39 and 39* has pivotally secured thereto at 45 a lever 46 one end of which bears upon the outer end of the headed member 41 while the other end thereof has pivotally secured at 47 a nut 48, said nuts 48 being in alignment. Threaded to said nuts 48 is a threaded member 49 having formed thereon intermediate said nuts 48 means such as the enlarged milled portion 50 turning said threaded member 49 about its axis.

In the operation of the device when it is desired to raise the movable member 12 the operating mechanism 19 is manipulated to 15 turn the spindle 18 and gear 17 formed thereon in a direction opposite to that indicated by the arrow α on Fig. 4 of the drawings. When this is done the ratchet 20 will 20 freely pass the pawls 21 without disturbing the train of gearing actuated by the driving gear 22, to which the pawls 21 are pivotally secured. During this operation the friction 25 pad 42 may be in contact with the face of the disk 37 or not as desired.

When the weight is lifted if it is desired 25 to retain it in its lifted position the threaded member 49 may be operated by the milled portion 50 to move the levers 46 about the pivots 45 so that the pads 42 will 30 be brought into frictional contact with the face of the disk 37 to prevent any movement of the gears. The load on the cap 13 would 35 tend to move the gears 17 and spindle 18 in a direction opposite to that indicated by the arrow α on Fig. 4. This reverse movement 40 would cause the pawls 21 to engage with the teeth of the ratchet 20 and as soon as the train of gearing has been locked from rotation by means of the friction pads 42, such reverse movement would be effectually prevented.

Whenever it is desired to lower the movable member 12 the friction pads 42 may be removed from the disk and with the pawls 45 21 in engagement with the teeth of the ratchet 20 the train of gearing will be driven by the rotation of the gear 17 and its spindle 18. This train of gearing is geared 50 up to such an extent that its inertia substantially retards the lowering of the jack and at the same time it produces a very high rate of speed for the revolute member 36 and the disk 37. Should an excessive load 55 be upon the cap 13 so that the member 12 moves downwardly too rapidly, the movement may be arrested by simply seizing the disk 37 by the hand or by forcing into contact with the side faces thereof the friction pad 42, the high rate of speed at which the 60 disk is driven acting to multiply the frictional power applied thereto so that a light pressure of a hand or friction brake will serve to instantly stop the descent of the jack, thereby making it possible for the 65 jack to be lowered very rapidly and yet to

be maintained at all times under control. If the brake were applied to the spindle 18 or geared thereto by a gearing having a small reduction ratio, it would be necessary to depend primarily upon the brake itself 70 not only to hold the load on the jack but to control its descent. The result of such an arrangement would be that the jack would descend in jerks, starting rapidly and requiring the application of strong brake 75 power to arrest it. It is to avoid the dangers incident to such operation of the jack that I have interposed the high ratio reduction gearing which has sufficient inertia 80 itself to largely resist any excessive speed of descent on the part of the jack under its load, and which at the same time greatly multiplies a light braking power so that the latter will stop the jack easily and without causing jerks or jars. When these pads 42 85 are in contact with the face of the disk 37 the rotation of the spindle 18 will be controlled through the train of gearing or may be arrested completely. It is obvious that when an extreme weight is supported by the 90 jack the tendency would be for the screw 15 to move downwardly in its nut 14 unless some provision was provided to effectually prevent such movement. It is self-evident that while, by the mechanism described, 95 such accidental lowering of the jack is wholly obviated, whenever it becomes necessary to lower the jack quickly by means of the operating mechanism such operation is possible.

It is believed that the operation and many advantages of the invention will be thoroughly understood from the foregoing.

Having thus described my invention, I claim:

1. In a quick action self lowering jack, the combination of a stationary member, a movable member, a revolute member for raising and lowering said movable member, a shaft, a gearing having a low ratio of speed reduction transmitting motion from said shaft to the revolute member, an extended train of gears having a high ratio of speed multiplication and adapted to act as a speed controller and retarder, a pawl and ratchet drive between said shaft and the low speed end of said multiplying gearing, and a freely and manually controllable friction member driven by the high speed end of said multiplying gearing, substantially as described.

2. In a quick action self lowering jack, the combination of a stationary member, a movable member, a revolute member for raising and lowering said movable member, a shaft, gears having a low ratio of speed reduction which connect said shaft and revolute member, an extended train of spur gears designed and adapted to produce a high ratio of speed multiplication, and to

act as a speed controller and retarder, a gear casing in which said gears are mounted, a pawl and ratchet drive between said shaft and multiplying gearing to disconnect the latter from the shaft when the latter is turned to raise the jack, a friction disk driven by the high speed end of said multiplying gearing and exposed to be controlled by hand, and brake means adjustable to positively engage said friction disk, substantially as described.

3. In a quick action self lowering jack, the combination of a stationary member, a movable member, a revoluble member for raising and lowering said movable member, a shaft, a driving connection between said shaft and revoluble member, an extended train of gears, a pawl and ratchet driving connection between the low speed end of

said train of gears and parts movable with 20 said movable member and adapted to drive said train of gears only during the descent of said revoluble member, said gears having a sufficiently high ratio of speed multiplication to substantially retard by its inertia the speed of descent of said movable member, a friction brake element driven by the high speed end of said train of gears, and a freely and manually adjustable brake which co-acts with said friction element, 25 substantially as described.

Signed by me at 4 Post Office Sq., Boston, Mass., this 26th day of February, 1912.

JOSEPH O. ST. PIERRE.
